United States Patent Office.

PETER M. KAFER, OF TRENTON, NEW JERSEY.

Letters Patent No. 94,610, dated September 7, 1869.

IMPROVEMENT IN FORCE-PUMPS HAVING CONCENTRIC PISTONS.

The Schedule referred to in these Letters Patent and making part of the same.

To whom it may concern:

Be it known that I, PETER M. KAFER, of Trenton, New Jersey, have invented new and useful Improvements in Double-Acting Force-Pumps; and I do hereby declare the following to be a full and exact description of the same, reference being had to the drawings that accompany and form part of these specifications, in which—

Figure 1 is a longitudinal bisection.

Figure 2, cross-section in line *m n*.

Figure 3, sectional view, showing the feed-valves.

A is an inside pump-cylinder.

B, the piston, working in the cylinder *A*.

C, piston-rod.

D, another cylinder, outside of and surrounding the cylinder *A*.

E, the piston working in *D* and over the cylinder *A*.

F and *F'*, the piston-rods working the piston *E*.

g g g are the induction-valves, four at each end of the box.

h h h h are the eduction-valves.

i i, valve-chambers.

z z, the source of supply, or supply-chambers.

z z, the exhaust-chambers, the valve-chambers *i i* connecting with the former by the inducting-valves *g g*, and with the latter by the educting-valves *h h*.

From the chambers *z z* the hose may lead off as desired.

The object of my invention is to provide more ready means of varying the capacity of a force-pump, and is especially adapted to steam fire-engines, where a variation is often required according to the distance of the engine from the fire.

My device allows of the working of several pistons at once, or of any one or more of the several at the same time. The various piston-rods may be connected together by any suitable mechanical device

that will provide for their being united or separated readily.

I am aware that pumps of some capacity for variation of this nature have been before used, but none possessing the modes of doing it or the qualities of mine.

I may work the inside piston *B*, leaving the piston *E*, or any others, if there are others, entirely at rest; or I may work *E*, and leave all the others at rest; or I may work two or more, and leave others, if there are more, at rest; or I may work all at one time. Thus, it will be readily perceived that all the pistons not actually in the act of forcing away the water, are at rest, and herein lies one of the features of my invention, and that is a great saving of friction, as other pumps, seeking the same ends, have all their pistons in motion, though producing no effect. This motion, simply in the case of packed or closely-fitting pistons, would use up much of the power or force of the engine.

I do not claim any given number of pistons; but

What I do claim, and desire to secure by Letters Patent, is—

1. Two or more concentric pistons, when operated throughout the length of the cylinder, as herein described.

2. The arrangement and combination of the valve-chambers *i i*, with relation to the supply and exhaust, substantially as specified and set forth.

In testimony whereof, I have signed my name to this specification, in the presence of two subscribing witnesses.

PETER M. KAFER.
